UNITED STATES PATENT OFFICE.

SAKUYE MIYAKE, OF SAN FRANCISCO, CALIFORNIA.

TIME-ALARM.

1,163,942.

Specification of Letters Patent. Patented Dec. 14, 1915.

Application filed March 18, 1915. Serial No. 15,311.

To all whom it may concern:

Be it known that I, SAKUYE MIYAKE, citizen of the Empire of Japan, residing at San Francisco, in the county of San Francisco and State of California, have invented 5 certain new and useful Improvements in Time-Alarms, of which the following is a specification.

This invention relates to alarm devices 10 and more particularly to an improved wrist watch accessory in which the alarm mechanism may be set to operate at a predetermined time to remind the wearer of a duty to be fulfilled or an act to be performed. 15 To this end the said invention consists in the construction and combination of parts to be hereinafter more particularly set forth and claimed.

In the drawings:—Figure 1 is an elevation of my improved time-alarm; Fig. 2 is a rear elevation, the back of the watch having been removed; Fig. 3 is a fragmentary cross sectional view (greatly enlarged) illustrating the interior operating or control 25 mechanism; Fig. 4 is an elevation of the complete device, the attaching means being shown extended; Fig. 5 is a plan view of a special type of bearing support; Fig. 6 is an edge view of said support; Fig. 7 illustrates 30 a plan and side elevation of a novel type of spring; Fig. 8 shows fragmentary views of certain specific parts; Fig. 9 is a detail perspective view of the stub shaft; and Fig. 10 is an elevation of the spring motor.

35 Like numerals of reference may be said to designate like parts throughout the several views.

Before proceeding with the description of the drawings I desire to call particular attention to the fact that while I have evolved 40 my invention with reference to its use as an improved wrist watch accessory or device, the same may be readily utilized in connection with a watch or time piece to be worn 45 upon the ankle or other part of the body.

In the drawings, 1 designates an ordinary 50 watch case equipped with suitable works of a character common to the art. The dial 2 however is arranged in spaced relation to 55 the normal front face of the watch herein designated 3 that the operating mechanism, shown to advantage in Fig. 3, may be interposed therebetween. The minute hand of the watch, designated 4 is mounted to turn with the shaft 5, while the hour hand 6 is mount-

ed to turn with the sleeve like structure 7, the said shaft 5 and said structure 7 being driven by the works (not shown) inclosed in the watch case 1. The sleeve like structure 7 is provided with a longitudinally extending key 8, said key, by reason of its locking engagement with a key way therefor formed in a cam face disk 9, imparting rotary movement to said disk yet permitting said disk to be moved or slid longitudinally 60 as will hereinafter appear. The cam face of the disk is designated 10.

An indicator 11 is operable over the face of the dial 2, the indicator being movable to register with one or the other of the dial numerals, thereby indicating or designating 70 the hour or exact time at which the alarm will be given. Said indicator 11 is made integral with a sleeve 12 arranged to embrace the sleeve like structure 7, the sleeve 12 being equipped at the end opposite from that from which the indicator 11 is formed with a disk 13 from the under face of which a pin 14 projects. The pin 14 is situated adjacent 75 the periphery of said disk 13 and is mounted to ride upon the upper cam face of the cam-disk 9.

A novel type of leaf spring, designated as 80 an entirety by the numeral 15, is provided to maintain cam disk 9 in positive engagement with the pin 14, said spring being affixed at one end as indicated at 16 to the casing part 3 and arranged to abut the opposite face of the cam disk from that designated 10.

The shaft 5, in order that the 85 spring may be held against lateral displacement, is arranged to penetrate the said spring, the opening for the shaft being shown at 17 in Fig. 7. The free end of the

spring 15 is inturned or extended at a right 90 angle as noted at 18, the extension penetrating the watch face and projecting beyond the rear face of the watch to provide an abutment for the alarm hand indicated 19.

Said alarm hand is equipped with a body 95 contact member 20 (preferably of an arcuate formation) and is made fast at its fixed end to a threaded extension 21 of a stub shaft or spindle 22. Spindle 22 is positioned concentric to the watch case or in axial alignment with shaft 5, a special type of bracket 23 in the nature of a bearing support affording a suitable means for maintaining the spindle or stub shaft in place. The bearing support 23 is of a spider formation, the re- 100

spective leg terminals being made fast as at 24 to the watch case back.

Beneath the bearing support 23 is arranged a spring motor 25; the said motor including a suitable casing 26, spiral spring 27 and gear 28. The spring 27 is mounted within the casing 26, one end of the spring being made fast with the inner wall of the casing, the opposite end of the spring having connection with the stub shaft 22 for imparting movement to the hand 19 as will subsequently appear. The teeth of gear 28 are in mesh with the teeth of a comparatively small gear 29, the latter being situated in adjacent proximity to the winding stem 30 of the watch and having a suitable gear connection therewith whereby to provide for a winding of the spring motor immediately previous to a setting of the alarm device 20 noted above.

If desired, the device may be provided with a lever 31 fulcrumed as at 32 intermediate its ends, the lever being movable as indicated in Fig. 2 to render the device operative or inoperative as occasion may demand. Said lever is situated in the path of movement of hand 19.

In operation, the indicating element 11 is moved in such relation to the dial of the watch as to indicate the hour or time at which the alarm is given, movement of the element 11 positioning the pin 14 upon the cam face 10 of the disk 9 as required. Movement is then imparted to the cam disk 9 by the driving force of the hour hand 6. As the hour hand is moved into parallelism with the indicating hand or element 11, pin 14 is caused by such movement to ride over the shoulder formed upon the cam face 10, thereby permitting the cam disk to move longitudinally of the sleeve-like structure 7, the moving force being derived through pressure generated in leaf spring 15. It is to be understood of course that the spring motor 25 has been previously rendered operative by a winding operation old in the art. As disk 9 is moved by the tension of spring 15, extension 18 of said spring is withdrawn from engagement with the alarm hand 19, thereby causing the said hand to rotate during unwinding of the spring 27 constituting the motor 25.

The outside back face of the watch is apertured as indicated at 33, the apertures being 55 of arcuate formation and disposed to coincide with the body contact member 20 as it is revolved through movement of hand 19. As said hand is revolved, body contact member 20 will operate in the slot 33 to thus engage 60 the wrist of the wearer and, by reason of the irritation created through its rapid turning movement indicate to the wearer the time at which he is to fulfil some obligation or perform some particular act.

Any suitable means such as is indicated 65 at 34 may be provided to retain the watch upon the wrist or other part of the body.

In reduction to practice, I have found that the form of my invention, illustrated in the drawings and referred to in the above description, as the preferred embodiment, is the most efficient and practical; yet realizing that the conditions concurrent with the adoption of my device will necessarily vary, I desire to emphasize the fact that various 75 minor changes in details of construction, proportion and arrangement of parts may be resorted to, when required, without sacrificing any of the advantages of my invention, as defined in the appended claims. 80

Having thus fully described my invention, what I claim as new and desire to secure by Letters Patent, is:—

1. In a time alarm, the combination with a time piece, of control mechanism associated with the time piece, a motor, a body contact member rotatable by the motor, and a spring arm conjunctively utilizable as a means for actuating said control mechanism when the mechanism is in an operative position and as a means for directly engaging and releasably holding the body contact member in an inoperative position. 85

2. In a time alarm, the combination with a time piece including hour and minute 95 hands, control means associated with the hour and minute hands and arranged at a predetermined time to move into an operative position, a spring arm for operating the control means when the latter is arranged in an operative position, a motor, a body contact member rotatable by the motor, and the free end of the spring arm being in engagement with the body contact member for releasing the contact member upon movement 100 of the spring arm. 105

3. In a time alarm, the combination with a time piece including hour and minute hands, control means associated with the hour and minute hands and arranged to move at a predetermined time into an operative position, a spring arm normally exerting a pressure on the control means for actuating the control means when the control means has been arranged in an operative 110 position, a motor, an arm rotatable thereby, a body contact member carried by the free end of the rotatable arm projecting through the time piece and engageable with the rotatable arm for releasing the arm simultaneously with the operation of the control means. 115

4. In a time alarm, the combination with a time piece, an alarm release cam operated thereby, a motor, a body contact member rotated by said motor, a spring arm with its free end engaging the body contact member to hold the motor against operation, said 120 125

spring arm also tending to move the cam in one direction and at the same time release the body contact member, and normally adjustable means for holding the cam against the action of the spring arm until the said cam has been moved to a predetermined position by the time piece.

In testimony whereof I affix my signature in presence of two witnesses.

SAKUYE MIYAKE.
